(57) **CLAIM**

The ornamental design for a filter retainer, as shown and described.

DESCRIPTION

FIG. 1 is a front perspective view of a filter retainer in accordance with my new design;

FIG. 2 is a top plan view of the filter retainer shown in FIG. 1; FIG. 3 is a bottom plan view of the filter retainer shown in FIG. 1;

FIG. 4 is a left elevational view of the filter retainer shown in FIG. 1;

FIG. 5 is a front elevational view of the filter retainer shown in FIG. 1;

FIG. 6 is a right elevational view of the filter retainer shown in FIG. 1; and,

FIG. 7 is a rear elevational view of the filter retainer shown in FIG. 1.

The broken lines shown in the drawings represent portions of the filter retainer that form no part of the claimed design.
